UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A BRUSH-BACK OR SIMILAR ARTICLE.

SPECIFICATION forming part of Design No. 26,250, dated November 10, 1896.

Application filed September 23, 1896. Serial No. 606,796. Term of patent 7 years.

To all whom it may concern:

Be it known that I, WILLIAM C. CODMAN, a subject of the Queen of Great Britain, residing at Providence, in the county of Providence and State of Rhode Island, have invented and produced a new and original Design for a Brush, of which the following is a specification, reference being had to the accompanying drawing, forming part thereof.

The drawing is a view of the back of a brush, showing my design.

The leading feature of my design consists in the raised ornamentations of the back of a hair-brush of conventional shape, consisting in a series of foliated scrolls interspersed with and partly overlaid by the floral ornamentations, as shown in the accompanying drawing.

A indicates the brush proper, and B the handle. The ornamentations are raised above the surface of the back of the brush and consist in the shell ornament 1 at the end of the handle, from which extend the two scrolls 2, inclosing the oval panel 3. The floral ornament 4 extends from the upper ends of the scrolls 2 between and partly extending over the scrolls 5. The contracted neck of the

handle near its junction with the brush-body has two scrolls covered with the floral ornament 6, and from this springs the foliated scroll 7, which connects the ornamentation of 30 the handle with the ornamentation of the brush-body A, in which the scroll 8, partly overlaid by the floral ornament, forms the lower margin of the central panel 10, the scrolls 11 11 and the floral ornaments 12 35 forming the sides of the ornamental border, and the foliated scrolls 13, the shell ornament 14, with the floral ornament 15, the upper part of the floral border inclosing the panel 10 and following the outline of the back of 40 the brush.

Having thus described my newly-produced design, I claim as new and desire to secure by Letters Patent—

The design for the back of a brush or similar article herein shown and described. 45

In witness whereof I have hereunto set my hand.

WILLIAM C. CODMAN.
